UNITED STATES PATENT OFFICE

ALBERT RETZER, OF MILWAUKEE, WISCONSIN

EGG CARTON

Application filed April 2, 1931. Serial No. 527,111.

This invention relates to improvements in egg cartons, and more particularly to the type adapted to receive a limited number of eggs for retail handling.

5 One of the objects of the present invention is the provision of a simple, inexpensive and efficient carton which, in addition to thoroughly protecting the eggs in the ordinary handling of the carton, is provided with 10 means for supporting the sections of the carton to prevent any heavy weights from pressing against the eggs arranged therein.

Another object of the present invention is 15 the provision of a novel type of egg carton, wherein the upper portion of the carton can be quickly and easily detached from the lower portion, whereby the lower portion will serve as a tray for the eggs, exposing the upper portions of the eggs so that they can be easily removed from the tray.

A further object of the present invention 20 is the provision of an egg carton having spacing means on the top and bottom thereof, so that a number of the cartons can be placed one on top of the other and at the same time relieve the direct pressure of the weight of the several cartons from the eggs in the lowermost cartons, so that a number of the 25 cartons can be piled one on top of the other for display purposes.

A still further object of the present invention 30 is the provision of an egg carton which can be made from a single piece of material, with the nesting portions arranged in opposed relation, and provided with a plurality of spaced egg receiving parts, and wherein the cover portion is attached to the body or 35 tray of the carton in such a manner as to permit its removal from the body so that the lower portion of the body will provide a 40 tray for display purposes, and also a tray wherein the eggs can be quickly and easily removed therefrom.

45 With the above and other objects in view, the invention consists in the novel features of construction, the combination and arrangement of parts hereinafter more fully set forth, pointed out in the claims and shown in the accompanying drawing wherein:

Figure 1 is a transverse sectional view on the line 1—1 of Figure 4;

Figure 2 is a detailed plan view of a portion of the blank;

Figure 3 is a transverse sectional view on the line 3—3 of Figure 4; and,

Figure 4 is a side elevation.

Referring to the drawing, it will be noted in Figure 2 that the blank 1 is provided along each side edge with spaced cutout portions 55 providing a plurality of small tabs 2 and a relatively large tab 3 at one side of the cutout.

A second row of cutouts lie parallel with the first row and suitable nests are formed in the second row of cutouts by providing 60 a central opening 4 and cutting out a plurality of tabs 5 around this central opening, the tabs to be bent inwardly to form the nest receiving portions, as shown in Figures 1 and 3.

The bottom or tray portions 6 of the carton 65 includes spaced channels 7 and 7', with one side of the blank folded across the channels, so as to position the nesting cutouts directly over the channels, whereby the eggs indicated A can be inserted in the nests, as illustrated. The cover 8 of the carton includes 70 the spaced channel members 9 and 9' adapted to be arranged in opposed relation with the channels 7 and 7' when the carton is closed, as shown in Figure 1. The tray portion 6 and the cover portion 8 are integrally 75 formed, but along the center of the blank a series of perforations 10 are formed whereby the cover can be readily detached from the 80 tray to provide an open tray, as shown in Figure 3.

It will be noted that when the carton is closed, as shown in Figure 1, the longitudinal 85 central portions 11 are arranged in superposed relation so that the two outer side members in which the nests are formed will rest one upon the other and the U-shaped parts 12 between each channel of both the tray and the cover rest upon the superposed parts 11, 90 as illustrated.

By cutting out the relatively large tabs 3 along the edges of the nesting parts, these 95 tabs will extend inwardly along the back of the carton, as shown in Figure 1, and will 100

engage the inner walls of the opposed channels so that weights placed upon the carton will not force the top and bottom of the carton onto the eggs. The front side of the 5 carton is supported by having the edges of the channels 7' and 9' arranged in intimate contact, as shown at the right in Figure 1.

From this, it will be apparent that the opposed channel members 7' and 7 and 9 10 are supported in spaced relation so as to relieve as much pressure as possible from the ends of the eggs.

In order to provide means whereby the cartons after being filled can be placed one 15 on top of the other, and relieve the pressure from the ends of the eggs in the cartons, the several channel members are provided in their intermediate portions with raised ribs 12'. These raised ribs not only reduce to a minimum the pressure against the eggs, but support the cartons in spaced relation with any 20 surface on which they may be resting, so as to provide a thorough circulation of air around the carton and prevent the accumulation of dampness which would have a tendency to penetrate through into the eggs and cause them to spoil.

Also, they serve to absorb shock when the 25 carton is set on a counter or table, thus preventing breakage, and in addition they act to prevent contact of the fastening button with the surface of the support, thus preventing scratching or marring of the same.

It will be noted from the foregoing that 30 I have provided a simple and inexpensive egg carton which consists of a top and bottom section connected with a line of perforations to permit the parts to be readily separated and in the line of perforation, I provide an arcuate 35 portion 10' which provides a tab 13 adapted to be inserted in one of the nests as shown in Figure 3, when the cover is removed from the tray, so as to retain the back wall of the tray in upright position.

40 It will be noted that by inserting the tab 13 in one of the nesting portions of the top of the tray, it will retain the rear side wall of the tray in close proximity to the top edge thereof and securely hold the eggs along 45 this edge in position.

Attention is also directed to the fact that 50 a well known type of button 14 can be attached to one channel of the cover 8. A cord 15 has one end attached to the button, while 55 the other end is passed around the carton and wound around the button to retain the cover 8 in closed position relative to the tray. It will be noted that by forming the relatively 60 large tabs 3 along each edge of the blank, that when these outer side portions of the blank are folded to provide the partitions between the tray and the cover, the relatively 65 large tabs 3 will be folded outwardly and engage the channels 7 and 9, so as to prevent 70 buckling or crushing of the carton along the

rear side, the front side being retained in position by having the opposed outer edges of the channel parts 7, 7', 9 and 9' arranged in intimate contact.

Again by having the U-shaped portions 75 12 of both the cover and the tray engage the superposed central parts 11 of the nesting members, the carton forms a substantial protection for the eggs.

Attention is also directed to the fact that 80 the ends of the carton are left open, thus providing a carton which can be formed from a single piece of material so as to reduce the cost of production of cartons of this character.

While I have shown and described the preferred embodiment of my invention, it 85 will be apparent from the foregoing that slight changes may be made in the construction 90 when putting the invention into practice without departing from the spirit of the same or the scope of the appended claims.

I claim:

1. An egg carton formed from a single 95 blank of cardboard folded upon itself to 100 form complementary top and bottom sections, each section having a pair of longitudinal troughs alined with the troughs of the adjacent section, inwardly folded partitions carried by each section and adapted to abut each other, said partitions being provided with spaced openings alined with said troughs and registering with each other, and struck-up tabs surrounding each of said openings for snugly engaging an egg, one of each 105 set of tabs adjacent the openings at the marginal edges of the partitions being elongated 110 for engagement with the wall of the adjacent trough to brace said wall and the marginal end of said partition.

2. An egg carton of a single blank of cardboard folded upon itself to form complementary top and bottom sections, each section having a pair of longitudinal troughs alined with the troughs of the adjacent section, inwardly folded partitions carried by each section and adapted to abut each other, said partitions being provided with spaced openings alined with troughs and registering with each 115 other, and struck-up tabs surrounding each of said openings for snugly engaging an egg, one of each set of tabs adjacent the openings of the marginal edges of the partitions being elongated for engagement with the wall of the adjacent trough to brace said wall and the marginal edge of said partition,

120 said carton being weakened along a medial line to provide a tab for the bottom section when the sections are severed, said tab being alined with one of the openings in the partition carried by the bottom section to permit said tab to be folded into the opening to lock the bottom section and partition together.

3. An egg carton formed from a single blank of cardboard folded upon itself to form complementary top and bottom sections, each section having a pair of longitudinal troughs aligned with the troughs of the adjacent section, inwardly folded partitions carried by each section and adapted to abut each other, said partitions being provided with spaced openings aligned with said troughs and registering with each other, struck-up tabs surrounding each of said openings for snugly engaging an egg, one of each set of tabs adjacent the openings at the marginal edges of the partitions being elongated for engagement with the wall of the adjacent trough to brace said wall and the marginal end of said partition, and longitudinal, outwardly projecting ribs formed on each trough portion to space the same from a support.

10

15

20 In testimony that I claim the foregoing I have hereunto set my hand at Milwaukee, in the county of Milwaukee and State of Wisconsin.

ALBERT RETZER.
